DUST CAP FOR BOTTLE

Chester A. Harlow, Easton, Pa., assignor to J. T. Baker
Chemical Company, Phillipsburg, N.J., a corporation
of New Jersey

Filed Apr. 1, 1960, Ser. No. 59,987

Term of patent 14 years

(Cl. D58—26)

Figure 1 is a top view of a dust cap for a bottle.

Figure 2 is a side view in elevation.

Figure 3 is a front view in elevation taken perpendicular to the line of sight of Figure 2.

The bottle and cap resting thereon shown in broken lines are for illustrative purposes only.

I claim:

The ornamental design for a dust cap for a bottle, as shown and described.
